United States Patent Office

Des. 211,561
Patented July 2, 1968

211,561

BOTTLE OR THE LIKE

Joseph Charles Pizzurro, Scarsdale, N.Y., assignor to Precision Valve Corporation, Yonkers, N.Y., a corporation of New York

Filed July 25, 1967, Ser. No. 7,966

Term of patent 14 years

(Cl. D9—82)

FIG. 1

FIG. 2

FIG. 3

FIG. 5

FIG. 1 is a perspective view of a bottle or the like, showing my new design;

FIG. 2 is a top plan view;

FIG. 3 is a front elevational view;

FIG. 4 is a side elevational view; and

FIG. 5 is a rear elevational view thereof.

I claim:

The ornamental design for a bottle or the like, as shown.
